UNITED STATES PATENT OFFICE.

CALVIN L. BUTLER, OF GREENFIELD, ASSIGNOR TO JOHN RUSSELL CUTLERY COMPANY, OF TURNER'S FALLS, MASSACHUSETTS.

CARVING-FORK.

SPECIFICATION forming part of Letters Patent No. 229,802, dated July 13, 1880.

Application filed January 7, 1880.

To all whom it may concern:

Be it known that I, CALVIN L. BUTLER, of Greenfield, State of Massachusetts, have invented a new and useful Improvement in Carving-Forks, of which the following is a specification.

The invention consists in providing a guard so hinged to the shank of a carving-fork as to serve also as a rest with a spring the free end 10 of which catches against one side or the other of the shoulder to keep the guard in position whether opened or closed.

In the drawings, Figure 1 is a plan of a carving-fork embodying my invention and showing the guard closed. Fig. 2 is a side view of same, also showing the guard closed, the dotted line, however, representing the position taken by the guard and its spring when the guard is open.

20 A is the shank, and B the guard, hinged to the shank at a. C is a spring-tongue, cast in one piece with the guard, and s is a shoulder, cast in one piece with the shank, and against one side or the other of which the free end of the spring catches, accordingly as the guard 25 B is closed or open, as seen in Fig. 2. The shoulder s is of such form that the free end of the spring can be carried over it in either direction with the requisite extra pressure upon the guard.

30 I claim—

In combination with a carving-fork having a shoulder formed on its shank, a hinged guard branching upon each side of the shank and provided with a spring-tongue, which 35 forms a part thereof and works in connection with said shoulder, substantially as described, for the purpose specified.
